FOUNTAIN TOOTH BRUSH

David W. Hamel, Westfield, Mass., assignor of
one-half to David W. Murdock

Application February 8, 1934, Serial No. 710,355

1 Claim. (Cl. 15—137)

This invention relates to a fountain tooth brush and has for an object to provide an improved fountain tooth brush wherein the tooth paste or dentifrice is placed in the handle within a cartridge containing the same.

A further object of this invention is to provide an improved fountain tooth brush wherein the handle contains a replaceable dentifrice cartridge.

Still a further object of this invention is to provide an improved fountain tooth brush which is provided with a cap for protecting the brush against contamination when not in use, enabling the same to be easily carried in the pocket or in a suitable case so the same may be available at any time for use in the home and can likewise be carried to the office, school or factory for noon-time use, and which cap further contains the mechanism for feeding the dentifrice from the cartridge in the handle to the bristles of the brush.

Still a further object of this invention is to provide a fountain tooth brush wherein the dentifrice is held in the handle protected against waste or soiling and yet is instantly available for use at any time when needed.

With the foregoing and other objects in view, as will hereinafter become apparent, this invention comprises the constructions, combinations and arrangements of parts, hereinafter set forth, claimed and illustrated in the accompanying drawings:

Fig. 1 is a side elevation of the invention.

Fig. 2 is a vertical sectional view of the same.

Fig. 3 is a sectional view of the fountain tooth brush in operating position.

Fig. 4 is a side elevation of the tooth paste cartridge.

Fig. 5 is an end view of the same looking from the left of Fig. 4.

Fig. 6 is an end view of the same looking from the right of Fig. 4.

Fig. 7 is a plan view of the paraffin composition cover for the said tooth paste.

Fig. 8 is a sectional view taken on the line 8—8 of Fig. 3.

Fig. 9 is a sectional view taken on the line 9—9 of Fig. 3.

Fig. 10 is a sectional view taken on the line 10—10 of Fig. 3.

Fig. 11 is a sectional view of an adaptable cap for fountain tooth brush.

There is shown at 10 the complete fountain tooth brush which as shown in Figs. 1 and 2 is in closed position for carrying the same in the pocket or otherwise, while in Fig. 3 it is shown in the

position ready for use. When in the closed position as in Figs. 1 and 2, as will be observed, the complete device resembles a fountain pen and is carried in the pocket in the same manner as a fountain pen.

The fountain tooth brush 10 comprises a barrel 11, which serves as a handle for the tooth brush 12, the tooth brush 12 being threaded as at 13 so that it may be detachably secured to the end of the barrel 11. The brush 12 is provided with four rows of bristles 14, the bristles being paired in two rows, each spaced apart as at 15.

A cap 16, having a pocket clasp 17 and ventilating holes 18, is adapted to be received over the end of the barrel or handle 11 when in open position and to be received over the brush 12 when in closed position. A plunger pin 19, secured within the cap 16, is threaded at its end as at 20 so as to hold the cap 16 in the closed position as shown in Fig. 2, the threaded end 20 cooperating with the threaded recess 21 in the brush 12. As will be seen in Fig. 20, the plunger pin 19 passes through the space 15 between the bristles 14 when the cap 16 is placed in closed position. The barrel of the handle 11 is adapted to receive a cartridge 22, made up of wax paper 23 and containing the tooth paste or dentifrice 24. This cartridge 22 is of such a size as to exactly fit within the barrel 11 and its ends 25 and 26 are perforated so that they can be torn off when the cartridge is placed in use, the end 25 being torn off after the cartridge is placed in position when the bristle holding member 12 is unthreaded from the barrel 11 as at 13.

The cartridge 22 is provided with a piston 27, the piston 27 being provided with a central depression 28 adapted to receive the end of the plunger pin 19. The end of the barrel 11 is closed by means of a cap 29 which has a hole 30 extending therethrough, allowing the plunger pin to pass through the hole 30 and into contact with the depression 28 of the wooden piston 27.

The bristle holding brush portion 12 is provided with a conduit 31, extending therethrough, and terminating in a pair of outlets 32, the outlets being placed in the space 15 so as to feed the dentifrice between the rows of bristles 14.

To load the cartridge 22 into the handle 11, the cap 29 is unthreaded from the end of the barrel handle 11, the end 25 of the cartridge is torn off, the cartridge 22, which is of wax paper with the dentifrice 24 therein, is inserted into the barrel. The perforated end 26 is then torn off and the cap 29 threaded into position. To operate the same, the plunger pin 19 of the cap 16 is then

passed through the hole 30 in the screw cap 29 and into the depression 28 of the wooden piston 27. The cap is merely then pressed gently over the barrel 11, causing the plunger pin 19 to press the piston pin 27 against the dentifrice 24, thereby causing a supply of dentifrice 24 to pass through the conduit 31 and outlets 32 between the bristles 14 of the brush 12. When the cartridge is empty, the plunger 27 will strike against the end of the brush 31, the end of the brush portion 12 being provided with bosses 33 which project into the depressions 34 of the piston 27 when the same comes in contact therewith.

As is apparent, the cartridge 22 containing the dentifrice 24 is convenient and easy for loading the barrel but it may sometimes happen that no cartridge is available and it is necessary to load the same from any conventional tooth paste tube, such as is shown at 35 in Fig. 11. To load it from a tooth paste tube 35, the screw-cap 29 is removed from the barrel 11 and the wooden piston 27 likewise removed therefrom. A special cap 36, threaded to fit the inside of the barrel 11, is screwed into position and this cap 36 is provided with an internal opening 37 to receive the nozzle 38 of the conventional tooth paste tube 35, allowing the dentifrice in the tooth paste tube 35 to be fed into the barrel 11. After the barrel 11 is filled in this manner, the piston 27 and screw-cap 29 are replaced into position, making the fountain tooth brush ready for use again. The brush handle portion 12 is threadedly connected as at 39 so as to enable the same to be detachably

secured to the barrel 11 and removed therefrom when necessary for thorough cleaning of the brush 12 and the conduit 31.

The novel features and the operation of this device will be apparent from the foregoing description. While the device has been shown and the structure described in detail, it is obvious that this is not to be considered limited to the exact form disclosed and that any changes may be made therein within the scope of what is claimed without departing from the spirit of this invention.

Having thus set forth and disclosed the nature of this invention, what is claimed is:

A fountain tooth brush comprising a hollow barrel defining a dentifrice reservoir, a bristle holding member secured to one end of said reservoir and having a conduit extending therethrough connecting said barrel with said bristles, a movable disc having a central depression at one end thereof within said hollow reservoir, said disc operable to force the dentifrice from said barrel to said conduit, an apertured cap secured to the opposite end of said reservoir, means for forcing said disc through said dentifrice reservoir, said means comprising a hollow member having a plunger pin fixed therewithin, said pin insertable through the aperture in said cap in contacting relation with said disc within said central depression for operating said disc, said hollow member adapted to be grasped to serve as a handle for said bristle holding member.

DAVID W. HAMEL.
